UNITED STATES PATENT OFFICE.

JOSEPH C. SEBRING, OF BISMARCK, KANSAS.

COMBINED CORN PLANTER AND CULTIVATOR.

SPECIFICATION forming part of Letters Patent No. 236,914, dated January 25, 1881.

Application filed May 23, 1880. (No model.)

To all whom it may concern:

Be it known that I, JOSEPH C. SEBRING, residing at Bismarck, Wabaunsee county, Kansas, have invented Improvements in Combined 5 Corn Planter and Cultivator, of which the following is a specification.

My invention consists in certain improvements in the construction of the seed-disk, devices for operating the seed-slide, of the marking mechanism, and other details of construction, hereinafter fully described, and pointed out in the claims.

In the drawings, Figure 1 is a longitudinal section of the corn-planter. Fig. 2 is a similar 15 view, showing the device as used for a cultivator. Fig. 3 is a detail view, in perspective, showing the device for operating the seed-slide of the corn-planter. Fig. 4 is a detail view of chain or cord mechanism by which the plows 20 are raised from the ground. Fig. 5 is a detail plan of the device used on the corn-planter to mark the next row. Figs. 6 and 7 are, respectively, a top view and a section, at *xx*, of a modification of the seed-slide dropper proper.

25 A is one of the ground-wheels. B is the draft-tongue. C is the endwise-adjustable seat-beam.

To the wheel A is attached, by any suitable means, a ring, D, having ratchet-teeth *d* on its 30 outside face, which are engaged by a spring-dog, E, working in socket E' secured to one of the spokes of the wheel A. These teeth *d* are so arranged that the ring D can be turned forward, but not backward.

35 D' D' are pins projecting from the ring D, which, as the wheel A revolves, come in contact with the arm F' of the bell-crank lever F operating the seed-slide. This lever F consists of an upright, F², stepped in one of the guide- 40 plates, g, between which the feed-slide G works.

To the lower part of the upright F² are attached two arms, F³ and F⁴. The arm F³ is attached to the feed-slide, and the arm F⁴ is connected, by a spiral or other spring, f', to a 45 standard, f², secured to the guide-plate g'. In the upper part of the standard f² are holes f³, in which works a rod, f⁴, attached to the arm F⁴.

It will thus be seen that as the wheel A revolves the pins D' on the ring D (as they come 50 in contact with the arm F' of the bell-crank and move the arm forward) move the feed-slide

in one direction. When the arm F' is relieved from the pin the seed-slide is drawn back by the spring f'.

The feed-slide G may have the usual seed-dropping device—that is to say, holes passing through it to receive the seed and carry it to the point of discharge. I claim no novelty in the construction of the seed-slide.

The shoes or opening-plows I of the planter 60 are of the usual construction. They are attached to the frame J, and raised and lowered by means of a hand-lever, K, through means of chains or cords L, one of which works on pulleys M attached to one of the cross-beams 65 of the frame N. The chains L are connected to a chain, L', passing directly up to a segment, O, upon the lever K. The chain L' laps around the periphery of the segment, so that as the lever is moved backward and downward the 70 chains and the plow-frame are drawn upward. The lever K is held back to sustain the plow-frame by a pawl, P, engaging with a segment ratchet or rack, Q. The pawl is drawn up to release it from the ratchet by a wire or rod, q, 75 and lever q'.

R is a foot-lever, fulcrumed to a hanger, R', and connected to the frame J by a link, R², to lift the frame, by depression of the rear end of the foot-lever, by means of the pressure of the 80 foot upon the stirrup-pin R³.

S is a hand-lever, fulcrumed to the seat-beam, the lower part of which is bent horizontally and supports a bail, T, attached by its forward ends to the shoes at t. When the bail is supported by the lever S it is above the rod f⁴. 85 The purpose of the bail T is to mark the last hill planted at the ends of the rows, and its operation is as follows:

When the last hills of each row are about 90 to be planted the upper end of the lever S is forced forward, dropping the bail on the pin or rod f⁴. Then, as the rod f⁴ is withdrawn from beneath the bail in the movement of the seed-slide, the bail is dropped, its ends or shares 95 t' entering the ground, marking the place where the last hills were planted. Through the means of this marker and the adjustable ring D cross-marking of the land is done away with, as all that is necessary to do is to move 100 the ring forward, so that the next pin D' will operate the feed-slide as the machine comes

opposite the marks made by the downward-projecting prongs t' of the bail T , which is, as above stated, the place where the last hills were planted.

5 U is a hanging bar or strut, attached to the seat-beam C by a pivotal connection, whose lower end rests upon the plow-frame J , (when the machine is in operation,) and holds said frame down. It has two or more holes, u , through any one of which its pivot-pin u' may pass, thus making it adjustable in length to regulate the depth to which the plows or openers I will enter the ground. The pin u' also serves as the support or fulcrum of the hanger R' and lever S . When it is desired to raise the shoes the lower part of the strut U is moved outward from contact with frame J by means of its handle U' .

10 To the back part of the shoes are secured scrapers V , by which the corn is covered with fine earth. The scrapers pass around the necks of the shoes in form of a strap, and are adjustable up or down by means of a pin, r , resting in notches r' in the heels of the shoes.

15 W is a marker for marking the next row to be planted. This is connected to the draft-tongue B by means of a staple, w , so that it may be used, whichever way the planter is traveling, by simply swinging it over from one side to the other. The marker has a double-ended runner, w' .

20 X are the draft-rods, working under pulleys or wheels Y in the hangers Z , (to which the shoes are attached,) and connected to the double-tree X' .

25 I will now proceed to describe the cultivator attachment, which is as follows: The frame J of the planter being removed, the beams a of the cultivator are attached to the hangers Z , braced to the frame by braces Z' , whose upper ends terminate in hooks z , to which are connected chains or rods b from the rear portion of the cultivator-beams to assist in their support. The chains or cords L are also connected to the beams a , and thus the beams may be raised by the hand-lever K in the same manner as the frame J .

30 Should it be desired to use my machine as a hand-planter, it is only necessary to place the bell-crank lever F on the other side of the seat-beam C , where it can be operated by hand.

In Figs. 6 and 7 is shown an oscillating seed-dropper, G' . This forms the bottom of the seed-box, and operates in the usual way by a part rotary reciprocation. It is pushed in one direction by the pressure of the end of the slide against a peripheral tooth, G^2 , and the return movement is caused by a spiral spring. (Shown in broken lines in Fig. 6.) If preferred, however, the dropper may be worked by wrist-connection with the slide G . G^3 is a plate forming the top of the disk, and held in place by two screws, g^3 , passing through slots g^5 in the plate. A hole is punched in the plate at g^2 , and from the metal punched down is made a lip, g^4 , forming one side of the seed-cavity g^2 .

35 It will be seen that by turning the plate G^3 the size of the seed-cavity g^2 is regulated to suit the size of the seed-corn and the number of seeds it is desired to have in the hill.

40 When planting in drills the corn may be dropped at each movement of the seed-slide G and disk G' .

45 In the present application I do not make any claim to the frame or mechanism for supporting and operating the shoes, reserving to myself the right to make a separate application therefor.

50 I claim as my invention—

1. The ring D , attached to the wheel A , and having notches d and pins D' , the former for engagement with a dog secured to a spoke of the wheel, and the latter operating on the arm F' of the lever F , and actuating the seed-slide, 55 in combination with the return-spring f' .

2. The combination of the pivoted bail T , having prong or share t' , the pivoted hand-lever S , slotted standard f^2 , tripping-rod f^4 , and bell-crank lever F , operated by ring D , 60 as and for the purpose set forth.

3. The combination, with the spring-retracted seed-disk G , having peripheral tooth G^2 , of the top plate, G^3 , made of a plate of sheet metal having slots g^5 g^6 , and provided 65 with screws g^3 g^3 , and having orifice g^2 , and down-turned lip g^4 , constructed and arranged as described.

JOSEPH C. SEBRING.
